AIR PRESSURE PUMP

Filed Jan. 23, 1932

FIG. 1.

Inventor

F. M. Gabler

By Watson E. Coleman
Attorney

UNITED STATES PATENT OFFICE

FRANK M. GABLER, OF MONUMENT, OREGON

AIR PRESSURE PUMP

Application filed January 23, 1932. Serial No. 588,441.

This invention relates to improvements in pumps and pertains particularly to a pump designed for injecting air under pressure into a container so that the contents of the container will be ejected by the compressed air therein.

The primary object of the present invention is to provide a pump structure by means of which air may be forced under pressure into a container of a fluid and valve means associated with the pump structure whereby a discharge passage leading from the lower part of the fluid receptacle may be opened so that the contents of the receptacle will be forced out by the compressed air therein.

A further object of the invention is to provide a pump structure of the above described character, wherein means is provided for employing the compressed air in the receptacle for clearing out the pipe line through which the liquid is led from the receptacle, after the required amount of liquid has been withdrawn, and the control valve has been closed, so that the discharge pipe or hose will not be left with a quantity of liquid therein.

A still further object of the invention is to provide a pump structure of simple, strong and durable and compact character and, therefore, capable of being readily mounted upon a small container such for example, as an oil or gasoline drum or the like.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view in side elevation of the air pressure pump structure embodying the present invention, parts thereof being in section;

Figure 2 is a longitudinal sectional view through a check valve element of the structure.

Referring now more particularly to the drawing wherein like numerals of reference indicate corresponding parts throughout the several views, the numeral 1 designates a portion of a tank or other receptacle, the same being shown in section and showing a threaded outlet or discharge aperture 2 in the wall thereof through which the draw-off pipe portion of the pump structure is extended.

The air pressure pump structure embodying the present invention comprises a tubular body portion 3 one end of which is enlarged and interiorly threaded as indicated at 4 to receive a threaded end of a draw-off pipe 5, which threaded end portion of the draw-off pipe is designed also for threaded engagement in the opening 2 of the receptacle 1 for the extension of the draw-off pipe into the receptacle in the manner shown, suitable washer elements or gaskets 6 being interposed between the lower end of the casting 3 and the receptacle and surrounding the pipe 5, to prevent leakage of air pressure from the receptacle.

The upper end of the casting 3 is also interiorly threaded as indicated at 7 and there is also carried by this upper end the laterally directed plate 8 which may be cast integral with the casting 3 if desired, in the manner shown. This plate 8 constitutes the lower head of a piston cylinder 9, the upper head for which is indicated by the numeral 10 and these heads are connected by the tie bolts 11 which draw the heads securely against suitable washers interposed between them and the ends of the cylinder 9.

The lower washer is indicated by the numeral 12 while the upper one between the head 10 and the cylinder 9 is not shown.

Threaded into the threaded upper portion 7 of the casting 3 is one end of a T coupling 13, the opposite end of which is interiorly threaded and is normally directed upwardly in the manner shown while the lateral outlet arm of the coupling is directed away from the cylinder 9 and has a pipe line 14 connected at one end therein, while the other end of the pipe line is suitably formed as indicated at 15 for the attachment of a hose

or other carry-off means thereto. In this pipe line 14 there is interposed a hand operated valve 16 of any suitable character, the type preferred being a reciprocable plug valve operated by a threaded stem 17 which is here shown in section, the usual hand wheel of which has been removed.

Threadably engaged in the upper end of the T coupling 13 is a reducing coupling 18, the smaller end of which is threadably engaged in one of the two aligned arms of a smaller T coupling 19, the other of the aligned arms of this coupling being directed upwardly, while the lateral arm thereof is directed in substantially the same direction as the lateral arm of the coupling 13 and is connected through the medium of a valve 20 with the small pipe 21 which leads to and is connected with the pipe line 14 upon the outside of the valve 16, or in other words, upon the side of the valve 16 remote from the coupling 13.

The upper arm of the small T coupling 19 has threadably engaged therein the downwardly opening check valve 22 which as shown in Figure 2, is controlled by a valve ball 23 which is normally forced upwardly against its seat by the spring 24 and the upper or inlet end of this check valve has connected therewith the small pipe line 25, the other end of which is connected by means of the coupling 26, with the lower end of the cylinder 9.

Extending longitudinally through the casting 3 and the larger T coupling 13 is an air pipe 27, one end of which is extended into the reducing coupling 18, while the other end, which extends into the upper end of the draw-off pipe 5, opens through the wall of this pipe to the exterior thereof so as to discharge into the interior of the receptacle 1.

The cylinder 9 has a piston 28 of any suitable character positioned therein and connected with this piston is the piston rod 29 which extends upwardly and through the upper head plate 10 where it is pivotally connected as indicated at 30 with a lever 31. The connection of the piston rod 29 with the lever 31 is inwardly of one end of the lever as shown and this adjacent end has pivotal connection as at 32 with a rocker arm 33 which is normally vertically disposed and has its lower end pivotally attached as at 34 to a bracket 35 which is rigid with the head plate 10. This bracket as shown, extends downwardly below the top end of the cylinder 9 and there is formed integral with it guide means 36 by which the rocker arm 33 is prevented from moving sideways.

From the foregoing description it will be readily apparent that when the air pressure pump embodying the present invention is mounted in a liquid receptacle in the manner illustrated and the valves 16 and 20 are closed, the operation of the piston 28 will

force air under pressure through the pipe 25 past the check valve 22 and down through the pipe 27 into the receptacle 1. Any desired pressure may thus be built up in the receptacle 1 above the liquid therein. After the desired pressure has been established in the receptacle this may be employed for removing some of the contents of the receptacle by opening the valve 16 so as to permit the liquid to be forced up through the draw-off pipe 5 the casting 3 and the T coupling 13 into and through the pipe line 14. After the desired amount of liquid has been removed from the receptacle the valve 16 is closed and the portion of the pipe line 14 lying beyond the valve 16 from the coupling 13 and the hose or other lead-off line which is connected with the pipe line 15, may be cleared of any liquid remaining therein by opening the valve 20, thus allowing the air under pressure to escape from the upper part of the receptacle 1 through the pipes 21 and 27 and into the outer end of the pipe line 14.

From the foregoing description it will be readily apparent that with an air pressure pump of the character herein described liquid may be readily drawn off from any receptacle by air pressure means and the air pressure may be kept established by an occasional operation of the piston 28.

Having thus described the invention, what is claimed is:—

1. In a pump structure of the character described, a pipe, means for securing the pipe to a receptacle with one end extending thereto, a coupling at the other end of said pipe having an upwardly and a laterally directed extension, a pipe line connected with said lateral extension and having a control valve therein, an air pump, a pipe line leading from said air pump and passing through said upwardly directed extension and extending longitudinally through a portion of said first pipe and opening through the wall thereof below the means for securing the same to a receptacle, a check valve in said last mentioned pipe, a pipe establishing an air passage between the pipe line leading from said air pump and the pipe line connected with the lateral extension of said coupling and entering the last mentioned pipe line at a point beyond the valve therein from the coupling, and a valve in said connecting pipe line.

2. A pump device for removing fluid from a receptacle by air pressure, comprising a pipe, means adjacent one end of the pipe for securing the same to a receptacle with the other end extending into the receptacle, a three way coupling having one way connected with the said one end of said pipe, a pipe line connected with another of the ways of said coupling and having a control valve therein, a reducing coupling in the third way

of said coupling and aligned with the first mentioned pipe, a second three way coupling having one way connected with the reducing coupling, a pipe connected at one end with said reducing coupling and passing longitudinally through the upper end of the first pipe and opening through the wall of the latter at a point below the said means, an air pump, a check valve controlled pipe line leading from said air pump into one of the ways of the second three way coupling, an air pipe line leading from the third one of the ways of the second mentioned three way coupling and entering said valve controlled pipe line at a point beyond the valve thereof from the first mentioned three way coupling, and a valve in the last mentioned air pipe line.

3. In a pump structure of the character described, a tubular body adapted to have one end extended into a receptacle, means intermediate the ends of the body for securing it to the receptacle, a bracket carried by the tubular body adjacent its other end, a pump structure mounted upon said bracket, a pipe connected at one end with the tubular body at the said other end, valve means controlling said pipe, a pipe connected at one end with said pump and having its other end extended into the tubular body through the said other end of the latter and opening through the wall of the tubular body at a point between the first mentioned end thereof and the means for coupling the same with

the receptacle, said last mentioned pipe having a check valve therein, and a valved pipe connected with the said last mentioned pipe between the check valve and the end thereof opening through the wall of the tubular body ⁷⁰ and having its other end entering the first mentioned valved pipe at a point between the valve and the outlet end thereof.

4. In a pump structure of the character described, a tubular body adapted to have one end extended into a receptacle, means intermediate the ends of the body for securing it to the receptacle, a pump, a pipe connected at one end with the tubular body at the said other end, valve means controlling said pipe, ⁷⁵ a pipe connected at one end with said pump and having its other end extended into the tubular body through the said other end of the latter and opening through the wall of the tubular body at a point between the first ⁸⁰ mentioned end thereof and the means for coupling the same with the receptacle, said last mentioned pipe having a check valve ⁸⁵ therein, and a valved pipe connected with the said last mentioned pipe between the check valve and the end thereof opening through the wall of the tubular body and having its other end entering the first mentioned valved pipe at a point between the valve and the outlet end thereof. ⁹⁰

In testimony whereof I hereunto affix my signature.
